CONTROL UNIT FOR COMPOSING MACHINES

Raymond R. Smessaert, Chicago, Ill., assignor, by mesne assignments, to Teletypesetter Corporation, Chicago, Ill., a corporation of Delaware

Application November 26, 1954, Serial No. 471,158

2 Claims. (Cl. 199—22)

This invention relates to control mechanisms for linecasting and composing machines and more particularly to apparatus for effecting the selective response of such machines to stored signal conditions.

The principal object of the invention is to provide facilities for effecting the simultaneous actuation of a plurality of normally individually responsive instrumentalities in response to a single stored signal.

Another object of the invention is to provide a means that is initially responsive to a certain code signal for controlling a certain function, and which is thereafter responsive to a different signal to control the same function.

Specifically, the arrangement according to the present invention recognizes a code signal formed by combining two existing code signals, so that recurring use, within a line, of one of the codes included in the combined code, occurring after the initial appearance of said combined code will cause the simultaneous selection of a space band and a fixed space, such as a thin space or an "en" space or an "em" space.

In the composition of material to be printed, it is the custom to finish all lines except certain short ones on a fixed right-hand margin. In composing machines of the linecasting type, this operation, called justification, is accomplished through the use of expandable spacebands to provide interword spaces. As a line is concluded, if the expansibility afforded by the included spacebands is sufficient to expand the line until it fills the required column width, the line is said to be justifiable. It may sometimes happen that a composed line which is short of justifiable length will not accommodate the next word or the next syllable of that word. The compositor may increase the length of the line by inserting fixed spaces, which are blank matrices of uniform thickness, adjacent the spacebands.

The subjection of linecasting and composing machines to automatic control, such as, for example, in the manner disclosed in Patent No. 2,091,286, granted August 31, 1937, to H. L. Krum et al., may necessitate special treatment with reference to nonjustifiable lines. Automatic control units of the type disclosed in the patent to H. L. Krum et al. may be controlled by perforated strips which may be produced by means of a keyboard perforator, such as the one disclosed in Patent No. 2,059,250, granted November 3, 1936, to H. L. Krum. The counting of the matrix thicknesses and minimum and maximum spaceband values cumulatively is accomplished concurrently with the application of the signals to the strip representing the matrices and spacebands to be assembled. The deficiency of a line is discovered after the signals have been applied to the tape, but individual signals for the selection of fixed spaces cannot then be inserted conveniently because the already punched signals follow one another at closely spaced intervals. It has been a practice heretofore to render the series of signals representing a deficient line ineffective by rerunning the signals through the perforator and converting each to the so-called rub-out or all-perforated signal.

2

This series of ineffective signals is then followed by a reperforation of the signals representing the line to be composed, with the fixed space signals included at the desired points. The sensing of the idle signals, when the control strip is run through the control unit for the linecasting and composing machine, accomplishes no useful purpose and results in a period of idleness of the composing machine.

In accordance with the present invention, it is proposed to control automatically the release of fixed spaces to accompany a deficient line, without the insertion of signals particularly associated with the release of fixed space matrices, and by the modification of one or more of the spaceband signals in the line. The modification comprises the perforation of an additional code hole or holes whereby the ordinary spaceband signal is converted into an extraordinary spaceband signal. It may be accomplished by backspacing the control strip through the perforator until that one or those of the spaceband signals that are to be converted from the ordinary to the extraordinary spaceband signal are aligned with the punches, and depressing the key lever assigned to the execution of an extraordinary spaceband signal, or by inserting the additional perforation or perforations by means of a hand punch or by an auxiliary punch block in the keyboard perforator provided for that purpose. No other modification of the signals in the tape is required, and none of the signals in the deficient line is destroyed.

According to an additional feature of the invention, a means is provided whereby the record sensing and pull bar selecting apparatus will be conditioned, upon responding to an extraordinary spaceband signal, for releasing a fixed space matrix in response to each subsequent spaceband signal in a line whether such subsequent spaceband signal is the ordinary spaceband signal or has been converted to the extraordinary signal. In other words, the mechanism will automatically add a fixed space to each succeeding spaceband for the remainder of the line, although the tape reader senses only a spaceband signal. At the end of the line the elevator mechanism will relatch the add-fixed-space mechanism permitting the unit to return to normal for the next line.

A full and complete understanding of the invention may be had by reference to the following description considered in the light of the accompanying drawings, in which:

Fig. 1 is a front elevational view of a portion of a linecasting and composing machine having an automatic control unit applied thereto;

Fig. 2 is a longitudinal sectional view of the record reader mechanism having embodied therein principles representative of the present invention;

Fig. 3 is a perspective view of the add-fixed-space mechanism according to the present invention;

Fig. 4 is a plan view of a fragment of control tape containing signals for releasing a spaceband alone, a fixed space matrix alone, and for releasing both simultaneously;

Fig. 5 is a sectional view taken on line 5—5 of Fig. 3.

Referring now to Fig. 1, the reference numeral 11 indicates generally a linecasting and composing machine. The linecasting machine has a conventional keyboard mechanism 12, matrix storage magazine 13, spaceband storage magazine 14, assembler belt 16, and an assembler elevator 17. The release of matrices from the matrix storage magazine 13 is effected by the lifting of release reeds 18, which may, if desired, be controlled from the keyboard 12, and the release of spacebands 19 from spaceband storage magazine 14 may be effected by the lifting of a special release reed 21, which may, if desired, be controlled by a manually operable spaceband key lever 22. A lever 23 pivoted intermediate its ends, as at 24,

has one end connected to the spaceband release reed 21, and has the other end connected to the spaceband escapement mechanism 26. The assembler elevator 17 has depending therefrom a link 27 which is articulated at its lower end to a crank arm 28 carried by a rock shaft 29.

Fig. 2 shows the manner in which the release reeds are lifted to effect the release of a matrix or a spaceband. Referring to that figure, it will be noted that key lever 31 pivoted as at 32, have tongues 33 in notches of individual weight bar 34, which are arranged to be lifted upon the rocking of a key lever 31 either manually or by automatic means. Each of the weight bars 34 is provided near its upper end with a notch in which is disposed one arm of a trigger bell crank 36, the other end of which normally supports a cam yoke 37 in such position that a keyboard cam 38, rotatably mounted in the cam yoke 37, is held out of engagement with a continuously rotating rubber roll 39. Each of the cam yokes 37 has a portion 41 disposed below a corresponding release reed 18 or 21. The release reeds 18 and 21 are notched to provide a shoulder which rests upon a supporting bar 42, and the notch 20 permits lifting the release reeds.

The lifting of a weight bar 34 by operation of a key lever 31 causes the rocking of the associated trigger bell crank 36 which frees the associated cam yoke 37 and permits it to drop until cam 38 engages rubber roll 39. Rotation is imparted to a cam 38 by rubber roll 39 which causes cam yoke 37 to be rocked counterclockwise (as viewed in Fig. 2) to lift the associated release reed 18 or 21. The lifting of cam yoke 37 by cam 38, returns it to the normal position where it is supported by trigger bell crank 36 in readiness for the next operation of the associated key lever 31 and weight bar 34.

Above each of the release reeds 18 there is a lever arm 43 pivoted as at 44 and having its free end adjacent to and in operative alignment with the escapement mechanism of a matrix storage channel of magazine 13 in well known manner. The lifting of one of the release reeds 18 causes its associated lever arm 43 to be rocked in clockwise direction (as viewed in Fig. 2) about its pivotal mounting 44 to cause its associated escapement mechanism to be operated and a matrix thereby released for transportation by assembler belt 16 to assembler elevator 17.

The present invention contemplates the operation of the keyboard mechanism 12 (Fig. 1) and of other instrumentalities of the linecasting machine, of which the assembler elevator 17, operable from the rock shaft 29, is an example, under the control of an automatic control unit which is indicated generally by the reference numeral 46, and which may be constructed in accordance with the teachings of the hereinbefore mentioned patent of Howard L. Krum et al. The automatic control unit 46 is attached to the linecasting machine 11 below and forward of the keyboard mechanism 12, and is arranged to be driven by power derived from any convenient continuously rotatable power shaft of the linecasting machine, such as the intermediate shaft 47 (Fig. 1). The power take-off for driving the automatic control unit may be a pulley 48 mounted on the intermediate shaft 47. Pulley 48 drives a belt 49 which engages a pulley (not shown) included in the record sensing mechanism indicated generally by the reference numeral 51 (Fig. 1).

The record sensing unit 51 controls a selecting unit which is contained within the housing 52 (Fig. 1), and the structural details of the record sensing unit 51 are shown in said Krum et al. Patent No. 2,091,286. The selecting unit comprises code bars 53 to which permuatational settings in accordance with the signal conditions sensed by the record sensing mechanism 51 are transmitted. Permutation code bars 53 are flat bars placed side-by-side and mounted for individual endwise movement between two selective positions. Connecting bars (not shown) engage each of the code bars 53 and ex-

tend into the record reading elements of the record sensing unit 51 to effect the selective positionment of the code bars 53. Code bars 53 are permutationally notched along the upper and lower edges, so that for each permutational setting of the code bars there may be established an alignment of notches extending across the entire permutation unit, which alignment may be in the upper and lower edges of the code bars 53. Selectable bars 57 extend transversely of the code bars 53 and are alternately disposed above and below the code bars. As shown in Fig. 2, each of the selectable bars 57 is fitted to a supporting rod 58 by means of notches, and springs 59 urge the selectable bar 57 rightwardly (as viewed in Fig. 2) to seat the selectable bars upon rod 58. Springs 59 also bias those selectable bars which extend below the code bars 53 clockwise, and those which extend above the code bars counterclockwise, whereby the selectable bars are urged to rotate into engagement with the code bars, and when permitted to rotate by the stripper or spreader cam 61, they move into engagement with the code bars and that selectable bar 57, which finds an alignment of notches, rotates farther than do the other selectable bars and enters the alignment of notches.

Each of the selectable bars 57 is provided on the edge 25 which is adjacent to the code bars 53 and near its forward end (left end, as viewed in Fig. 2) with a shoulder 62 which is presented in the path of universal bail 63 upon selection of the selectable bar 57 by entrance of that bar into an alignment of notches. Universal bail 30 63 is shown in its normal or unoperated position in Fig. 2, and when it is actuated by the shaft which carries spreader cam 61, it is moved leftwardly (as viewed in Fig. 2) and engages the shoulder 62 of any selectable bar 57 which has been selected, and imparts endwise movement leftwardly to that bar.

Each of the selectable bars 57 which is assigned to the release of a matrix or a spaceband has in alignment with it the depending arm of a bell crank lever 64 which is pivoted on mounted shaft 66. The horizontal arm of each of the bell cranks 64 is disposed above and substantially in engagement with a forwardly extending portion 67 of an auxiliary key lever 68 pivoted on common pivot 69. There is an auxiliary key lever 68 for and below each of the manually operable key levers 31, and each of the key levers 68 has a tongue 71 which is disposed in a notch in one of the weight bars 34. It will be apparent from this that any one of the weight bars may be lifted to trip the associated cam yoke 37 by depressing the forward end of the associated key lever 31, or by depressing the foremost portion 67 of the associated auxiliary key lever 68. It will also be apparent that leftward movement of a selected one of the pull bars 57 by universal bail 63 will cause clockwise rocking of the associated crank lever 64, which will depress the forward end of its associated auxiliary key lever 68 to lift the corresponding weight bar 34. The patent to Howard L. Krum et al. hereinbefore identified, may be consulted for a full detailed description and showing of the apparatus thus far described.

As outlined hereinbefore, it is necessary to provide for the addition of fixed space matrices to be assembled adjacent to some or all of the spacebands. This may be accomplished by bringing back into registry with the punch pins in the perforator those of the spaceband signals representing spacebands with which fixed space matrices are to be assembled, and converting them from the ordinary spaceband signal 101 indicated in Fig. 4 as a single perforation in the code element "3" position to an extraordinary spaceband signal 102 by the addition of a perforation in the code element "0" position. When fixed space matrices are required as a regular part of the composition without reference to spacebands or the filling out of a deficient line, they are represented by a code 103 having a single perforation in the code element "0" position. Thus, by combining the attributes

of both the spaceband signal and the fixed-space signal, both a spaceband and a fixed-space will be selected simultaneously.

With the arrangement according to the present invention, means is provided whereby the selector apparatus will be conditioned, upon responding to the "0-3" or extraordinary spaceband signal, for releasing a fixed-space matrix in response to each subsequent spaceband signal in a line whether such subsequent spaceband signal is the ordinary spaceband signal or has been converted to the extraordinary signal. In other words, in the practice of the invention, means is provided in a linecasting and composing machine for releasing spacebands and fixed spaces simultaneously in response to a predetermined code signal which comprises changing only the first spaceband signal in the line pursuant to which the mechanism will automatically add a fixed space to each succeeding spaceband for the remainder of the line, whereupon the elevator signal will restore the arrangement to normal condition. This result is accomplished by providing an arrangement response to the "add-fixed-space" code signal to effect substantially simultaneous operation of both the special fixed-space and spaceband bell cranks 64, as will hereinafter appear.

Referring to Fig. 3, there are shown certain selectable bars of the group of selectable bars 57, individually identified as the "fixed-space" selectable bar 72, the "spaceband" selectable bar 73, the "add-fixed-space" selector bar 74 and the "elevator" selectable bar 75. Appropriately positioned above the group of selectable bars 57 (of which bars 72 to 75 are members) is a shaft 76 suitably journaled in the frame of the control unit 46. Suitably positioned on said shaft 76 with respect to said selectable bars 72, 73 and 74 are individual actuators 77, 78 and 79, respectively. The actuator 77 is adapted to be adjustably clamped on shaft 76 by means of set screw 81. Moreover, actuator 77 cooperates with a shoulder 82 on bar 72.

Pivottally connected to actuator 78 is a rearwardly extending connecting member 84 which terminates in a hook portion 85 adapted to cooperate with a supporting member 86 mounted on a pivot 87. Member 86 is normally biased in a clockwise direction (as viewed in Fig. 5) about pivot 87 by a spring 88 and normally rests against a stop 89. The hook portion 85 of member 84 cooperates with a shoulder 91 on the supporting member 86. Connecting member 84 is provided between its pivot 92 and hook portion 85 with a pair of spaced depending portions 93 and 94 which are arranged in the manner of a fork and are adapted under predetermined operating conditions to operably engage a stud 95 secured to the bar 73, as will presently appear. Member 86 is provided with a latch portion 96 adapted to cooperate with a latch element 97 pivoted at 98. Latch 97 is normally biased clockwise by a spring 99 against a release bar 100 affixed to the elevator selectable bar 95.

In the rest condition of the arrangement according to the present invention, actuator 77 is clamped on shaft 76 in such a position as to be presented in the path of shoulder 82 on the "fixed space" selectable bar 72. Also, the actuator 78 is fixed on the shaft 76 in such position as to be presented in the path of shoulder 83 of spaceband selectable bar 73. Furthermore, the actuator 79 is fixed on the shaft 76 in such position as to be presented into the path of the shoulder 104 on the "add-fixed-space" selectable bar 74.

In the operation of the device according to the invention, it is assumed that the elements of the structure are in their normal unoperated position, as shown in Fig. 3, with the actuators 77, 78 and 79 positioned on the shaft 76 in the manner shown. Pursuant to the reading of the tape 105 (Fig. 1) by the reading unit 51, the code bars 53 are set permutatively to produce an alignment of notches therein so that a selected bar 57 (or 72 to 75) will enter said alignment of notches in order to effectuate

its operation by the operating bail 63, as described in said Patent No. 2,091,286.

Thus, in response to the spaceband signal (code element "3" position), which is the position 101 in Fig. 4, 5 the selectable bar 73 will be selected and the bell crank 64 individual thereto will be operated to effect through its associated reed 21, Fig. 1 (as disclosed in Patent No. 2,091,286), the counterclockwise rocking of lever 23 about pivot 24 to operate the spaceband escapement 10 mechanism 26 to release a spaceband 19 from the spaceband storage magazine 14. It will be noted hereinafter that the spaceband selectable bar 73 may also be selected in response to the extraordinary spaceband code signal 102 (Fig. 4).

15 Now, in response to a "fixed-space" signal (referred to also as the "thin-space" signal) which is in the position 103, Fig. 4, exemplified by the code element "0" position, the selectable bar 72 identified with the thin space position in the matrix storage magazine 13 will be selected 20 and operated so that a "thin-space" matrix (also called "fixed-space," because actuator 77 may be positioned on shaft 76 to control the release of an "en space" or "em space" matrix, if desired) will be released to drop upon the assembler belt 16 and be conveyed to the assembler 25 elevator 17.

As previously mentioned, it is desired to simultaneously select a spaceband and a "fixed-space" matrix (called the "add-fixed-space" function). In this event, the spaceband signal (code element "3" position) is changed to an 30 "add-fixed-space" signal (code element 0-3). However, in the preparation of tape for controlling the apparatus according to the present invention, it is not necessary to modify every spaceband signal in order to effect the release of a fixed-space matrix simultaneously therewith, 35 but it is only necessary to modify one spaceband signal (normally the first spaceband signal in the line) to convert said ordinary spaceband signal into an extraordinary spaceband signal, in order to effect the release of a fixed-space matrix with that spaceband and with all following 40 it in the line.

Now, pursuant to the receipt of the extraordinary spaceband signal (102, Fig. 4) both of the bars 73 and 74 will be selected, so that as a result of the forward motion imparted to bars 73 and 74 by the operating bail 63, a 45 spaceband will be released upon operation of the bell crank 64 individual to bar 73, and substantially simultaneously therewith, a fixed space matrix will be released because the shoulder 104, of bar 74 will act upon actuator 79 to rotate shaft 76 to, in turn, cause actuator 77 to 50 rotate correspondingly to move bar 72 forwardly to rotate the bell crank 64 identified therewith to effect the release of a "fixed-space" matrix from the magazine 13.

Concurrently with this operation of the mechanism (shown in Fig. 3) to effect the initial simultaneous release 55 of a spaceband and "fixed-space" matrix, said mechanism will be conditioned for thereafter releasing a spaceband and a "fixed-space" matrix simultaneously in response to only a spaceband signal (101, Fig. 4) in the following manner:

60 In response to the selective operation of bar 74 pursuant to the receipt of the extraordinary spaceband signal 102, the actuators 79, 78 and 77 are rotated a predetermined amount, as previously described. Upon rotation of actuator 78, the connecting member 84 pivottally 65 articulated thereto is moved forwardly to impart, through the coaction of shoulder 91 and hook portion 85, counterclockwise rotation to member 86 against the action of spring 88. Member 86 will be thus rotated to the position shown in Fig. 5, whereat member 84 is permitted 70 to drop sufficiently to permit the fork members 93 and 94 to straddle and engage the stud 95. Member 86 will become latched in this position by the engagement of latch element 97 with the tooth 96. Thereafter, whenever a spaceband signal alone is received, the bar 73 is 75 actuated forwardly to release a spaceband, and substan-

tially simultaneously therewith the connecting member 84, through the fork and pin connection 93, 94, 95 is actuated (or carried along forwardly with the bar 73) to impart rotation, through actuator 78, to shaft 76 which in turn will impart corresponding rotation to actuator 77 to impart through shoulder 82, forward motion to the bar 72, which, through its individual bell crank 64 will effectuate the selection of a "fixed-space" matrix from the magazine 13, as previously described.

As is disclosed in said Patent No. 2,091,286 to H. L. Krum et al., the matrices and spacebands are assembled in the assembly elevator 17, and upon receipt of the elevator signal at the end of the line, the elevator 17 is raised to carry the assembled line of matrices to the casting position in well known manner. Upon the sensing of the elevator signal in the tape 105 by the tape reader 51, the code bars 53 will be set permutable to effect the selection of the elevator selector bar 75 (one of the bars 57) to effectuate the elevator operation, which comprises releasing the elevator cam (not shown) for one cycle of rotation, as described in said Patent No. 2,091,286. Also, bar 75 will be effective through the release bar 100 affixed thereto, to effect the release of latch element 97 from tooth 96 to permit the return of supporting member 88 from its position shown in Fig. 5 to its position shown in Fig. 3, under the influence of spring 88. Pursuant to this return of member 88 against its stop 89, the connecting bar 84 will be lifted or raised by the member 86 to bring the fork members 93 and 94 clear of the pin or stud 95, thus disconnecting the mechanical connection between bar 73 and the connecting bar 84. Therefore, pursuant to the selective operation of the elevator selector bar 75, the arrangement according to the present invention is restored to the normal condition shown in Fig. 3, preparatory to setting up the next line.

Although a preferred form of the invention has been disclosed and described, it is obvious that changes may be made in the details set forth without departing from the essentials of the invention.

What is claimed is:

What is claimed is:

1. In a linecasting and composing machine, means for releasing fixed thickness space elements, means for releasing variable thickness space elements, a permutation code selector, first and second selectable members controlled by predetermined permutative settings of said selector for individually controlling said means, respectively, a third selectable member controlled by a further permutative setting of said selector, said selectable members carried pivotally on a common rod, an auxiliary shaft disposed above and parallel to said common rod, a plurality of actuators carried on said auxiliary shaft, one of said actuators operably associated with each of said selectable members, said first selectable member adapted to control the release of a fixed thickness space element, said second selectable member adapted to control the release of a variable thickness space element, cooperating means associated with both said second selectable member and its actuator, said cooperating means effective under certain operating conditions to control the release simultaneously of a fixed thickness space element and a variable thickness space element upon each selective operation of said second selectable member, said cooperating means comprising a connector bar articulated to one of said actuators, said connector bar having fork instrumentalities cooperable with a stud instrumentality on said second selectable member, conditioning means cooperably associated with the free extremity of said con-

riector bar, said conditioning means comprising a pivoted element normally effective to hold said fork instrumentalities out of cooperative engagement with said stud instrumentality, said pivoted element and said connector bar

- 5 having cooperating facilities, whereby said connector bar is effective upon the first selective operation of said second selectable member to establish the cooperative engagement of said fork and stud instrumentalities during subsequent operations of said second selectable member,
- 10 latching means for holding said conditioning means effective during said subsequent operations of said second member, a fourth selectable member, and means operably associated with said fourth selectable member for rendering said latching means ineffective.

15 2. In a linecasting and composing machine, means for releasing fixed thickness space elements, means for releasing variable thickness space elements, a permutation code selector, a pair of selectable members controlled

20 by predetermined permutative settings of said selector for individually controlling said means, respectively, a further selectable member controlled by a further permutative setting of said selector, said selectable members carried pivotally on a common rod, an auxiliary shaft disposed above and parallel to said common rod, a plu-

25 rality of actuators carried on said auxiliary shaft, one of said actuators operably associated with each of said selectable members, one of said pair of selectable members adapted to control the release of a fixed thickness space element, the other of said pair of selectable members adapted to control the release of a variable thickness space element, means for conveying an assembly of type composition elements and space elements, control means 30 for said actuators, and a means for selectively operating said actuators.

for said conveying means, cooperating means associated with both said second selectable member and its actuator, 35 said cooperating means effective under certain operating conditions to control the release simultaneously of a fixed thickness space element and a variable thickness space element upon each selective operation of said second selectable member, said cooperating means comprising

40 a connector bar articulated to one of said actuators, said connector bar having fork instrumentalities cooperable with a stud instrumentality on said second selectable member, conditioning means cooperably associated with the free extremity of said connector bar, said conditioning means comprising a pivoted element normally effecting

50 ing into the comprising parts of the instrumentality, effective to hold said fork instrumentalities out of cooperative engagement with said stud instrumentality, said pivoted element and said connector bar having cooperating facilities, whereby said connector bar is effective upon the first selective operation of said second selectable member to establish the cooperative engagement of said fork and

55 to establish the cooperative engagement of said first and stud instrumentalities during subsequent operations of said second selectable member, latching means for holding said conditioning means effective during said subsequent operations of said second member, and means controlled by said control means for said conveying means for rendering said latching means ineffective.
